UNITED STATES PATENT OFFICE.

WILLIAM C. BRINTON, JR., OF KENNETT SQUARE, PENNSYLVANIA, ASSIGNOR TO
PHILIPS-BRINTON COMPANY, OF KENNETT SQUARE, PENNSYLVANIA, A COR-
PORATION OF PENNSYLVANIA.

CONTACT MAKER AND INTERRUPTER.

1,234,275.

Specification of Letters Patent. Patented July 24, 1917.

Application filed July 24, 1915. Serial No. 41,665.

To all whom it may concern:

Be it known that I, WILLIAM C. BRINTON, Jr., a citizen of the United States, residing at Kennett Square, county of Chester and 5 State of Pennsylvania, have invented a new and useful Improvement in Contact Makers and Interrupters, of which the following is a full, clear, and exact description, reference being had to the accompanying drawings, which form a part of this specification.

The object of my invention is to provide an improved means for opening and closing the primary circuit in a single spark ignition system for gas-driven automobiles. In 15 such a system it is necessary that the circuit should be closed only momentarily in order to avoid a quick jump in amperage. It is also necessary that the contact should be 20 made with certainty, whatever the number of cylinders contained in the engine, at maximum, minimum and all intermediate speeds, and under all the varying conditions arising in actual use.

More specifically, the invention is an improvement upon the construction heretofore patented by me under date of February 23, 1915, No. 1,129,445 and No. 1,129,446, although the present invention contains certain 25 features that do not necessarily embody the inventions of said patents.

The causes of defective operation in devices of this character that experience discloses are various and not always determinable. Slight defects in manufacture, 35 ordinary wear and tear, inevitable vibration, and vertical displacement of the timer-shaft due to the causes mentioned or to any other cause, frequently cause the timing of 40 the device to vary to an extent that precludes proper operation. Again, due sometimes to the foregoing causes, but more especially to the great inertia of the parts, the mechanism between the timer-shaft and the relatively 45 stationary contact does not always return sufficiently quickly, causing chattering and irregularity.

Again, it is very desirable to economize space and to mount the device upon as small 50 a base as practicable, to which end compactness of construction is highly desirable.

My present invention is designed to avoid

these sources of trouble and imperfect operation and to attain the desirable results mentioned.

55

A preferred embodiment of the invention is shown in the accompanying drawings, in which—

Figure 1 is a plan view of the contact device and immediately coacting parts; Fig. 60 2 is an elevation partly in section; Fig. 3 is a side view of the contact device; Fig. 4 is a detail view of one of the contacts.

The cam-shaft or timer-shaft *a* extends up through a base *b* (which may be made 65 hollow to afford a condenser chamber) and carries a head *c* of insulating material to which is secured the distributor conductor plate *d*. A cap *e* of insulating material fits upon the base *b* and incloses the top of shaft 70 *a*, the head *c* and the contact device herein-after described. The cap *e* carries the common terminal post *f* and the binding posts 1, 2, etc.; the secondary current being closed successively through the several binding 75 posts as the shaft *a* revolves, in a manner well known in the art.

On the base *b*, surrounding the shaft *a*, is a boss *v*. Above the boss *v* and sleeved upon the shaft is a disk *w* having teeth or 80 cams *g*. Above the disk *w* and sleeved upon the shaft is a flanged collar *x*. Projecting downward from the flange of the collar *x* is a pin *x'* which enters a hole in the disk *w*. A radial screw *y* extends through collar 85 *x* and is threaded in the shaft *a*. The head *c* has a vertical key-way *z*. Thus, the collar *x* is fixed to shaft *a*, the disk *w* is fixed to collar *x*, and the head *c* is driven from collar *x*.

90

The teeth or cams *g* correspond in number to the number of cylinders comprised in the engine.

Secured to the base *b* is a strip or plate *h* having a flange *i* bent upward and then 95 parallel to the plate *h*. Between the plate *h* and the overhanging part of the flange *i* near one end of the plate *h*, is pivoted, on a vertical axis, a bell-crank tripper lever *k*. Pivoted on the end of lever *k* nearest the 100 shaft *a* is a yoke-shaped lever or head *m*, the arms of which embrace the end of lever *k*. This head *m* has a pointed or beveled end in line of travel of the teeth *g* whether

the shaft be rotating in one direction or the other. The connecting member of head *m* is normally held against one side of the lever *m* by the spring *n* which, at one end, 5 is secured to a small projection in line with said connecting member, the other end of the spring being attached to the contact plunger bar *p* hereinafter described. Therefore, when the shaft *a* is turning in its normal forward direction, as indicated by the 10 arrow in Fig. 1, it actuates the head *m* and lever *k*, against the tension of spring *n*, as if they were one piece, thereby swinging lever *k* on its axis; while if the shaft *a* be 15 turned backward, the head *m* is swung in the opposite direction on its own axis, against the tension of spring *n*, without imparting any movement to lever *k*.

At the end of the plate *h* opposite that 20 near which lever *k* is pivoted is a rigid yoke *o* through which slides the plunger *p*. The front end of this plunger is bent up and provided with a contact nose *p'* in the direction of extension, or of the sliding 25 movement, of the plunger. The opposite end of the contact plunger is cut away to afford a shoulder *p*² opposite which normally extends the end of lever *k* more distant from the shaft *a*.

Immediately beyond the nose *p'* of the plunger *p* is the end of a contact pin *r*. This pin has a shoulder which closes the 30 open end of an adjustable holder *s* having a head *s'*. Between the head *s'* and the shoulder, the pin *r* is of relatively small diameter and is surrounded by a coil spring *t*, which normally holds the contact end of the pin at a definite distance from the nose of the plunger *p*. The holder *s* is threaded 35 in a bracket *u* projecting from a block *u'*, which is of insulating material, or is insulated from the base *b*. The washer *r'* on the outer end of pin *r*, limits the movement of the pin in the direction of the plunger *p*. 40 The apparatus is wired so that the current from the battery passes to the contact device shown in Fig. 4, thence to the plunger contact *p* and thence through the base *b* and back to the battery.

50 The single spring *n* is arranged to perform a variety of functions. It holds the upturned end of contact plunger *p* against the yoke *o*, which thus acts as a stop. It holds the plunger *p* against its front and rear guides, one upright arm of the yoke *o* acting as a front guide and the edge of the vertically extending part of the flange *i* acting as a rear guide. It holds the tripper lever *k* against the vertically extending part 55 of flange *i*, which acts as a stop. It holds the pivoted head *m* against the tripper lever *k*. During the swinging movement of the tripper lever, in its actuation by one of the teeth *g*, after said lever contacts with and slides the plunger *p*, the 60

70 tension of the spring increases and thereby increases the pressure of plunger *p* against its front and rear guides. When the tripper lever has overridden the plunger *p*, the spring draws back the plunger at a maximum speed due to the increased tension on the spring, thereby insuring accurate contact and a clean, quick break. When a tooth *g* has overridden the head *m* of the tripper lever, the spring, under further increased tension, returns the tripper lever against its stop and displaces the plunger *p* laterally. Finally, in case of reverse rotation of the shaft *a*, it returns the head *m* of the tripper lever to normal position. 75

80 From the foregoing description, the operation of the device will be readily understood. When a tooth *g* strikes the head *m* of the tripper lever *k*, it first swings the tripper lever against the shoulder on the contact plunger *p*, then, by a sliding movement along said shoulder, pushes the plunger *p* longitudinally until its contact nose *p'* impinges against, and slightly moves, the contact pin *r*. Immediately thereafter the 85 end of the tripper lever *k* slides off the shoulder on plunger *p* and the spring *n* returns the plunger, immediately after which the tooth *g* slides off the head *m* and the 90 spring *n* returns the tripper lever *k*, the plunger *p* swinging laterally to allow the tripper lever to return.

95 It is obvious that the contact pin *r* may be adjusted to regulate its extent of movement when impinged against by the nose of the plunger contact and thereby regulate the duration of contact.

100 It will also be obvious that vertical displacement of the shaft *a* will not affect the character or duration of contact between its teeth and the head of the tripper lever.

105 The construction is such that the inertia of the parts is reduced to a minimum. One of the main structural features whereby this is accomplished is provision for sliding, instead of swinging, the contact bar *p* against the contact pin *r*, which, when so engaged, itself slides in the direction of its axis.

110 Having now fully described my invention, what I claim and desire to protect by Letters Patent is:

115 1. A contact maker and interrupter comprising a contact, a coöperating contact member having a differential movement and adapted in one movement to directly engage the contact and in another movement to move relatively to the contact without engaging the same, a shaft, actuating means adapted in its movement in opposite directions to engage the contact member and impart to it one or the other of its movement dependent upon the direction of movement of said actuating means, and a shaft controlling the operation of said actuating means, said contact and contact member 120

125

130

forming the termini of an electric circuit which is momentarily closed by their engagement as specified.

2. A contact maker and interrupter comprising a contact slidable in a right line and restrained from movement otherwise, a coöperating contact member having a differential movement and adapted in one movement to directly engage the contact and in another movement to move relatively to the contact without engaging the same, a shaft, actuating means adapted in its movement in opposite directions to engage the contact member and impart to it one or the other of its movements dependent upon the direction of movement of said actuating means, and a shaft controlling the operation of said actuating means, said contact and contact member forming the termini of an electric circuit which is momentarily closed by their engagement as specified.

3. A contact maker and interrupter comprising a contact, a slidable and swingable contact member adapted in its sliding movement to directly and momentarily engage the contact and in its swinging movement to move relatively to the contact without engaging the same, actuating means adapted in its movement in opposite directions to impart to the contact member its sliding and swinging movements respectively, and a shaft controlling the operation of said actuating means, said contact and contact member forming the termini of an electric circuit which is momentarily closed by their engagement as specified.

4. A contact maker and interrupter comprising a contact slidable in a right line and restrained from movement otherwise, a coöperating contact member having a sliding movement in a right line parallel to that of the contact and having also a swinging movement, actuating means adapted in its movement in opposite directions to engage the contact member and impart to it its respective movements, and a shaft controlling the operation of the actuating means, said contact and contact member forming the termini of an electric circuit which is momentarily closed by their engagement as specified.

5. A contact maker and interrupter comprising a contact, a slidable and swingable contact member adapted in its sliding movement to directly and momentarily engage the contact and in its swinging movement to move relatively to the contact without engaging the same, actuating means adapted in its movement in opposite directions to impart to the contact member its sliding and swinging movements respectively, a spring adapted to return the contact bar to normal position when slid or swung away therefrom, and a shaft controlling the operation of said actuating means, said contact and

contact member forming the termini of an electric circuit which is momentarily closed by their engagement as specified.

6. A contact maker and interrupter comprising a contact movable in one direction, a coöperating contact member movable longitudinally in the same direction and also having a swinging movement, actuating means adapted in its movement in one direction to engage said contact member and slide it longitudinally and thereby cause it to engage and move said contact and in its movement in the other direction to swing said contact member, a spring adapted, in said movement of said contact, to be compressed and to return said contact to normal position after the retraction of the contact member, and a shaft controlling the operation of said actuating means, said contact and contact member forming the termini of an electric circuit which is momentarily closed by their engagement as specified.

7. A contact maker and interrupter comprising a contact movable in one direction, a coöperating contact member movable longitudinally in the same direction and also having a swinging movement, actuating means adapted in its movement in one direction to engage said contact member and slide it longitudinally and thereby cause it to engage and move said contact and in its movement in the other direction to swing said contact member, a spring adapted, in said movement of said contact, to be compressed and to return said contact to normal position after the retraction of the contact member, a spring adapted to so retract said contact member, and a shaft controlling the operation of said actuating means, said contact and contact member forming the termini of an electric circuit which is momentarily closed by their engagement as specified.

8. A contact maker and interrupter comprising a contact forming one terminal of the circuit, a slidable contact member forming another terminal of the circuit, a rotatable member, and a pivoted lever adapted to be actuated thereby to slide the contact member into direct and momentary engagement with said contact.

9. A contact maker and interrupter comprising a slidable contact forming one terminal of the circuit, a contact member forming another terminal of the circuit, a rotatable member, and a pivoted lever adapted to be actuated thereby to engage a rear end portion of said contact member and push it bodily into engagement with said contact.

10. A contact maker and interrupter comprising a spring pressed contact pin adapted to yield in the direction of its axis, a spring-retractable contact member adapted to move bodily toward said pin in a direction sub-

125
130
135

- stantially parallel to the latter's axis and thereby close the circuit, a rotatable member, and a pivoted lever adapted to be actuated thereby to impart said bodily movement to the contact member.
- 5 11. A contact maker and interrupter comprising a contact forming one terminal of a circuit, a contact plunger forming the other terminal of the circuit and slideable in the direction of its length toward the first contact, a rotatable member, and a pivoted lever adapted to be actuated thereby to engage and move said plunger longitudinally and thereby close the circuit through said contacts.
- 10 12. A contact maker and interrupter comprising a contact forming one terminal of the circuit, a sliding contact member, a rotatable member, and a pivoted lever one end 15 of which is operable by the rotatable member and the other end of which is adapted to push the sliding contact member into circuit-closing engagement with said contact, the axes on which said rotatable member 20 turns and said lever swings being parallel.
- 25 13. A contact maker and interrupter comprising a contact forming one terminal of the circuit, a movable contact member, a lever adapted to move the contact member 30 into circuit-closing engagement with said contact, a rotatable member adapted to actuate the lever, and a single retracting spring one end of which is connected with the lever and the other end of which is connected with the contact member.
- 35 14. A contact maker and interrupter comprising a contact forming one terminal of the circuit, a slideable contact plunger and guides therefor, a lever adapted to push 40 the plunger into circuit-closing engagement with said contact, a rotatable member adapted to actuate the lever, and a single retracting spring connecting the lever and plunger and adapted to return them to normal position and hold the plunger against its guides.
- 45 15. A contact maker and interrupter comprising a contact forming one terminal of the circuit, a contact plunger slideable in the direction of its length, guides for the 50 plunger, said plunger being also displaceable laterally, a lever adapted in its advance movement to push the plunger into circuit-closing position and on its return movement to displace the plunger laterally, a rotatable member adapted to actuate the plunger, and a single retracting spring connecting the lever and plunger and adapted to hold the plunger against its guides in its forward movement and return the plunger and lever 55 to their normal positions.
- 60 16. A contact maker and interrupter comprising a contact forming one terminal of the circuit, a contact plunger cut away at its rear to form a shoulder and tail piece, 65 guides engaging the front of the plunger and said tail piece, a lever adapted in its forward movement to engage said shoulder and push the plunger into circuit-closing position, a rotatable member adapted to so actuate the lever, and tension means to return the plunger and lever.
- 70 17. A contact maker and interrupter comprising a contact forming one terminal of the circuit, a sliding contact plunger, a lever adapted in its advance movement to engage and slide the plunger, a head pivoted on the lever and adapted when actuated in one direction to move the lever with it and when actuated in the other direction to swing freely on the lever, a rotatable member 75 adapted to actuate said head in opposite directions, and tension means to return the parts to normal position after actuation by the rotatable member.
- 80 18. A contact maker and interrupter comprising a contact forming one terminal of the circuit, a sliding contact plunger, a lever adapted in its advance movement to engage and slide the plunger, a head pivoted on the lever and adapted when actuated in one direction to move the lever with it and when actuated in the other direction to swing freely on the lever, a rotatable member 85 adapted to actuate said head in opposite directions, and a spring connecting said head 90 and plunger.
- 90 19. A contact maker and interrupter comprising a contact forming one terminal of the circuit, a sliding contact plunger, a guide and stop at the front of the plunger, the rear 95 of the plunger being cut away to form a tail-piece and shoulder, a guide and stop for said tail-piece, the rear of the plunger being also laterally displaceable, a bell-crank lever one arm of which is adapted, in the advance 100 movement of the lever, to engage said shoulder and slide the plunger into engagement with said contact, a stop for said lever, a head pivoted on the other arm of the lever and adapted when actuated in one direction 105 to advance the lever and when actuated in the other direction to swing freely on the lever, a rotatable member adapted to actuate said head in opposite directions, and a spring attached at opposite ends to the 110 plunger and head and adapted to return and normally hold the plunger, lever and head in their normal inoperative positions.
- 110 20. A contact maker and interrupter comprising a horizontal base, an upright shaft 115 extending therethrough, a cam disk sleeved on the shaft, a collar on the shaft and pinned to the disk, means securing the collar to the shaft, and primary circuit interrupting mechanism mounted on said base and operable from the cam disk.
- 120 21. A contact maker and interrupter comprising a horizontal base, an upright shaft extending therethrough, an annular boss above the base and surrounding the shaft, a 125

cam disk sleeved on the shaft and resting on said boss, a collar on the shaft and resting on and pinned to the disk, means securing the collar to the shaft, and primary circuit interrupting mechanism mounted on said base and operable from the cam disk.

22. A contact maker and interrupter comprising a horizontal base, an upright shaft extending therethrough, a cam disk sleeved

on the shaft, a collar on the shaft and 10 pinned to the disk, a set screw fixing the collar to the shaft, and a secondary circuit distributor cap sleeved on the shaft and having a vertical key way engaging said screw.

In testimony of which invention, I have 15 hereunto set my hand, at Philadelphia, on this 22nd day of July, 1915.

WILLIAM C. BRINTON, JR.

Correction in Letters Patent No. 1,234,275.

It is hereby certified that in Letters Patent No. 1,234,275, granted July 24, 1917, upon the application of William C. Brinton, Jr., of Kennett Square, Pennsylvania, for an improvement in "Contact Makers and Interrupters," an error appears in the printed specification requiring correction as follows: Page 2, line 123, claim 1, and page 3, lines 11-12, claim 2, strike out the words "a shaft"; and that the said Letters Patent should be read with this correction therein that the same may conform to the record of the case in the Patent Office.

Signed and sealed this 14th day of August, A. D., 1917.

[SEAL.]

R. F. WHITEHEAD,
Acting Commissioner of Patents.

Cl. 123—168.
